(57) **CLAIM**

The ornamental design for a spray wrench scraper, as shown.

DESCRIPTION

FIG. 1 is a perspective view of a spray wrench scraper of the invention;

FIG. 2 is a front view of the spray wrench scraper depicted in FIG. 1;

FIG. 3 is a back view of the spray wrench scraper depicted in FIG. 1;

FIG. 4 is a left side view of the spray wrench scraper depicted in FIG. 1;

FIG. 5 is a right side view of the spray wrench scraper depicted in FIG. 1;

FIG. 6 is a top view of the spray wrench scraper depicted in FIG. 1; and,

FIG. 7 is a left side view of the spray wrench scraper depicted in FIG. 1.
